UNITED STATES PATENT OFFICE.

JESSE ALEXANDER, OF BROOKLYN, NEW YORK, ASSIGNOR, BY MESNE ASSIGNMENTS, TO LEE ALEXANDER, KITIE ALEXANDER, JR., JESSE ALEXANDER, JR., AND TYVE ALEXANDER.

TYPE-WRITING MACHINE.

No. 833,282.

Specification of Letters Patent.

Patented Oct. 16, 1906.

Application filed June 2, 1902. Renewed November 1, 1905. Serial No. 285,369.

To all whom it may concern:

Be it known that I, JESSE ALEXANDER, a citizen of the United States, residing at Brooklyn, in the county of Kings, State of New York, have invented certain new and useful Improvements in Type-Writing Machines, of which the following is a full, clear, and exact description.

My invention relates to improvements in the construction of type-writing machines, and particularly to the key and type bar construction and mechanism therefor.

The particular construction herein shown and described is adapted for use with a visible-writing type of machine, such as shown more fully in my other applications filed herewith, Serial Nos. 109,925, 109,927, and 109,928.

The object of this invention is to secure a construction of the key and type bar mechanism and the supports and arrangement of the same which may be easily assembled and will be held securely in place and be easy of operation.

The construction will be found to be economical and to provide a positive and certain action with a touch which is very desirable. It consists in a construction as hereinafter to be described, and shown in the drawings.

Figure 1 is a side elevation and sectional view of the key and type bar mechanism and a platen. Fig. 2 is a detail of a portion of the key-bar-locking support. Fig. 3 is a detail of the locking-plate. Fig. 4 is a detail of the end of the key-bar. Figs. 5, 6, and 7 are details of construction of a key. Fig. 8 is an enlarged detail of the end of a type-bar. Fig. 9 is an end view of the type-bar and block. Fig. 10 is a vertical projection of the type-bar plate. Fig. 11 is an enlarged detail of the type-block-alining device. Fig. 12 is a detail of a section on the line X X of Fig. 10.

In the particular form of mechanism shown in the drawings, A is a key-bar pivoted at *a* in a key-bar-supporting plate B. The end of the key-bar is formed by stamping sheet metal, as shown in Fig. 5, then twisting the end, as shown in Fig. 6, and lastly folding it down to the form shown in Fig. 7. The plate B is slotted, as shown at *b*, to receive the end of the key-bar and a recess cut in that part of the supporting-plate

which lies between the keys, in which recesses the pivots of the key-bars rest. After the key-bar pivot has been inserted in the recesses of the supporting-plate B a locking-plate C, having projections or fingers *c'*, is put in place on the bar *c* above the key-bar-supporting plate and secured thereon to lock the pivots in the recesses in which they fit.

It will be noted that all of the key-bars after having been put in place may all be locked at the same time by the locking-plate C, which plate to make the adjustment more perfect may be slotted at *c* to coact with the screws by which it is attached to the supporting-plate B.

D is what may be termed an "intermediate" lever, which is pivoted at *d* in the lever-supporting plate E. The construction of this lever-supporting plate and its locking means is similar to that of the key-bar-supporting plate and locking means. The method of inserting these intermediate levers is similar to that of inserting the key-bars. The intermediate lever carries at one end, conveniently to be engaged with the key-bar, two small bearings or rollers *d*² *d*³, which are adapted to give a smooth and rolling contact between the key-bar and intermediate lever. The key-bars may be notched at *a'* to permit of the ready assembling of the parts.

The key-bar may be provided at its underneath portion with a small spring-finger *a'* to assist in holding it in its proper normal position.

The intermediate lever may be drawn up to its normal position by a spiral spring *d*³, which for purposes of adjustment may be secured at one end to an adjusting-screw *e*, working in the intermediate-lever-supporting plate or its equivalent.

The type-bar F is pivoted at *f* in a slot of the type-bar plate G in a manner similar to the pivoting of the key-bar and intermediate levers in their respective supports. A cross-section of a support is clearly shown in Fig. 12. These key-bar slots may be arranged substantially in a semicircle, as shown in Fig. 10. The lower end or tail of the type-bar is curved down and back, as shown, to engage with the guide bars or rollers *d*⁴, carried by the intermediate lever.

It will be noted that the intermediate lever is constructed in such a peculiar manner that

when in its normal position, as shown in full lines in Fig. 1, the weight of the parts is very nearly balanced about the pivot d , so that the action of the mechanism is made much more smooth and easy.

I have shown in Fig. 1 the key and type bar mechanism in full lines in the normal position of rest and in dotted lines in the position in which they would be when printing.

If desired, the type-bar plate G may carry an adjustable stop-screw g in line with the positions which the type-bars will take when printing for the purpose of regulating the blow which the type-block may deliver upon the platen H . When the type-bars are in their normal or rest position, the back of the end of the type-bar or type-block may rest upon a pad held in place in the supporting-guide J .

In the construction of the type-bar and type-bar block which I have preferred to use and have shown herein in Figs. 1 and 9 the type-block f^2 is preferably made separate from the type-bar and of such a form as to engage with the end of the type-bar and be adjusted thereon by means of screws fitting in a slot f^3 , as in Fig. 8, at the end of the type-bar.

The type-bar plate G (indicated in Fig. 1 in section) is shown in vertical projection in Fig. 10. In this latter figure will appear more clearly the alining-posts K K , in which are set the ball-bearings for alining the type-blocks at the striking or printing position. These posts are, as shown, preferably adjusted about their pivots L by means of set-screws working in coöperation with a projection from the upper part of the type-bar plate. To assist in holding these alining-posts in their proper operative positions, I have provided a peculiar-shaped spring-like brace or arm extending from the posts at either side. The outer end of these spring-braces M M may be secured by screws to the type-bar plate G and being integral with the post will afford a means for holding the set-screw of the post in operative engagement with the projection from the type-bar plate.

If it is desired, the ball-bearings k' may be provided with adjusting-screws k^2 , as shown more clearly in Fig. 11, so that the requisite degree of freedom of action of the balls may be provided. For the purpose of more securely holding the adjusting-screw k^3 in place I have provided in Fig. 11 set-nuts, as shown. The method of adjustment of the position of the alining-posts, it is thought, will be obvious from an inspection of the drawings. It has been found preferable to adjust the distance between the balls k' by changing the position of the alining-posts, the balls themselves having, as above mentioned, been given previously their proper freedom of movement in their holding-sockets.

It will be noted on inspection of Fig. 1

that the positioning and proportions of the parts of the type and bar movements are so effected that the touch of the mechanism is most easy and perfect. As before mentioned, the intermediate lever D may be balanced most readily upon its pivot d' when in its normal position of rest. In this position, as shown in full lines, the weight of the key-bar is disposed in such a way that the turning moment about its pivot due to its weight will be when once started forward very nearly equal to the turning moment of the type-bar F about its pivot f due to its weight with associated parts. When a key is depressed, it is therefore merely necessary, in order to bring the type into printing position to give a force sufficient to overcome the adjusted tension of the springs a^2 and d^3 , operating, respectively, in conjunction with the key-bar A and intermediate lever D . As the type-bar ascends and the amount of force necessary to raise the type-block to its printing position in contact with the roller increases it will be noted that the length of the key-bar is a constant, while its arm which acts to draw the intermediate lever down is decreasing—but very slightly in going to the dotted position. At the same time the lever-arm of the type-bar by which the turning moment is transmitted from the intermediate lever gradually increases as the bearings d^4 travel down the curve of the tail F' . In this way while the force due to the touch of the operator's finger may be approximately a constant quantity during the stroke the type-block gathers considerable momentum as it approaches the printing-surface, so that a sharp impact is produced at the upper end of the stroke. This is sufficient to move the universal bar N . In this way a movement is effected which is specially efficacious in manifolding, where a strong, sharp, and sudden blow of the type upon the pivot is absolutely necessary in producing clear and distinct manifold copies. This effect of increase of the striking force of the blow is further heightened by the fact that when the intermediate lever is once started from its balanced position in full lines its weight is almost immediately thrown upon the side, which would tend to further add to the force of the blow. When adjusting the levers in their proper positions to get the tension desired, the small spring d^3 , which regulates the position of the intermediate lever, may be adjusted by means of the adjusting-screw e in simple manner. In a similar manner the pressure of the adjusting spring-finger a^2 may be effected.

At N is shown in section a small portion of the end of the universal bar, which, as its name implies, is located in such position as to be operated by the shoulder n of any one of the type-bars just previous to the printing position. On an inspection of Fig. 1 it will

be noted that this universal bar will not be moved to the right and thrown into operation until the type-bar has nearly reached its uppermost position, so that when the 5 type-bar is started to the printing position it is necessary that it should have passed by its position of possible failure and be certain to proceed to the platen before the universal bar will be reached. In this way I have provided 10 a construction in which the universal bar will not be operated except by a touch which positively operates the type-bar to its printing position. The method of operation beyond this point of the universal bar is not 15 shown in this application, since its preferred form is covered in another application which is filed for the purpose. Among the functions of the universal bar which is common to machines generally of this type is that of 20 operating the ribbon movement and the carriage movement. The universal bar being situated directly back of the type-bar pivots insures a quick and powerful blow delivered at the proper instant.

25 The keyboard may be arranged as desired; but it is preferred to have it of the two-case or single-shift class in which each type-block is provided with two type-faces.

Obviously many of the advantages of construction could be utilized in other forms of machines; but it is particularly valuable in the type of visible-writing machines.

What I claim is—

1. In a type-writing machine, a key-bar, a 35 spring-finger adjustment therefor, an intermediate lever, means for connecting said lever with said key-bar, a spiral spring adjustment for said lever, a type-bar and an arm curved downward and outward and projecting from 40 said type-bar for engagement with said intermediate lever, substantially as described.

2. In a type-writing machine, a pivoted key-bar, an intermediate lever pivoted above said key-bar, a roller-bearing connection between 45 one end of said lever and said key-bar, a type-bar pivoted above said lever and having a downward and outwardly projecting curved arm for engagement with a roller-bearing connection on said intermediate lever.

50 3. In a type-writing machine, a key-bar, an intermediate lever, means for connecting said bar and lever, a type-bar and a rolling means of connection between said lever and said type-bar, a curved projecting arm from 55 said type-bar for coacting with said means of connection so that as said type-bar is raised its operating-lever arm increases in length, substantially as described.

4. In a type-writing machine, a key-bar, 60 an intermediate pivoted lever, means for connecting said bar and lever, a type-bar and a

rolling means of connection between said lever and said type-bar, a curved projecting arm from said type-bar coacting with said means of connection so that as said type-bar 65 is raised its operating-lever arm increases in length, and a shoulder carried by said type-bar back of said pivot for engagement with a universal bar, substantially as described.

5. In a type-writing machine, a key-bar, 70 an intermediate lever, a type-bar, rolling means of connection between said intermediate lever and said key and type bars, said intermediate lever having a backwardly-projecting arm and a spiral spring connected at 75 one end of said arm and at the other to an adjusting-screw, substantially as described.

6. In a type-writing machine, a key-bar, 80 an intermediate lever, a type-bar, a pair of roller-bearings carried by said intermediate lever for engagement with said key-bar, said key-bar having indentations as shown for the purpose of assembling the parts, and means of connection between said intermediate lever and said type-bar, substantially as de- 85 scribed.

7. In a type-writing machine, a key-bar, 85 an intermediate lever, a type-bar, a pair of roller-bearings carried by said intermediate lever for engagement with said key-bar, a 90 second pair of roller-bearings carried by said lever for engagement with said type-bar, substantially as described.

8. In a type-writing machine, a key-bar, 95 an intermediate lever, a type-bar, a rolling connection carried at one end of said intermediate lever for engagement with said key-bar, and a pair of roller-bearings carried by the other end of said lever for engagement with a curved projecting arm of said type-bar, sub- 100 stantially as described.

9. In a type-writing machine, a key-bar, 105 an intermediate lever, a type-bar, a pivot for said lever, a forwardly-projecting arm of said lever carrying roller-bearings for engagement with said key-bar, an upwardly-projecting arm of said lever carrying roller-bearings for engagement with a curved projecting arm of said type-bar, substantially as described.

10. In a type-writing machine, a pivoted 110 key-bar, an intermediate lever pivoted above the key-bar, a roller-bearing connection between one arm of said lever and said key-bar, a pivoted type-bar having a projecting curved arm, and a roller-bearing connection 115 between said curved arm and one arm of said intermediate lever.

JESSE ALEXANDER.
